[57] CLAIM

The ornamental design for a headset ear piece, as shown.

DESCRIPTION

FIG. 1 is a perspective view of a headset ear piece showing my new design;
FIG. 2 is a top view thereof;
FIG. 3 is a front view thereof;
FIG. 4 is a left side view thereof;
FIG. 5 is a right side view thereof;
FIG. 6 is a rear view thereof;
FIG. 7 is a bottom view thereof;
FIG. 8 is a perspective view of an alternate embodiment of FIG. 1;
FIG. 9 is a top view of FIG. 8;
FIG. 10 is a front view of FIG. 8;
FIG. 11 is a left side view of FIG. 8;
FIG. 12 is a right side view of FIG. 8;
FIG. 13 is a rear view of FIG. 8;
FIG. 14 is a bottom view of FIG. 8;
FIG. 15 is a perspective view of an alternate embodiment of FIG. 1;
FIG. 16 is a top view of FIG. 15;
FIG. 17 is a front view of FIG. 15;
FIG. 18 is a left side view of FIG. 15;
FIG. 19 is a right side view of FIG. 15;
FIG. 20 is a rear view of FIG. 15; and,
FIG. 21 is a bottom view of FIG. 15.
